US0D1049939S

(12) **United States Design Patent** (10) Patent No.: **US D1,049,939 S**
(45) Date of Patent: ** Nov. 5, 2024

(54) **STROLLER**

(71) Applicant: **Royalty Bugaboo GmbH**, Zug (CH)

(72) Inventors: **Dejan Kamenski**, Amsterdam Z.O. (NL); **Marco Nieuwenhuizen**, Amsterdam Z.O. (NL); **Stephanie Wirth**, Amsterdam Z.O. (NL)

(**) Term: **15 Years**

(21) Appl. No.: **35/516,270**

(22) Filed: **Feb. 17, 2022**

(80) **Hague Agreement Data**

Int. Filing Date: **Feb. 17, 2022**

Int. Reg. No.: **DM/221098**

Int. Reg. Date: **Feb. 17, 2022**

Int. Reg. Pub. Date: **Feb. 17, 2023**

(51) **LOC (14) Cl.** **12-12**

(52) **U.S. Cl.**

USPC **D12/129**

(58) **Field of Classification Search**

USPC D12/129, 133

CPC B62B 7/00-04; B62B 9/00-28

See application file for complete search history.
